J. MINTZ.
CHECK PERFORATOR.
APPLICATION FILED MAR. 31, 1919.

1,333,089.

Patented Mar. 9, 1920.

INVENTOR
Julius Mintz.
BY
Maurice Block,
ATTORNEY

UNITED STATES PATENT OFFICE.

JULIUS MINTZ, OF NEW YORK, N. Y.

CHECK-PERFORATOR.

1,333,089.

Specification of Letters Patent.

Patented Mar. 9, 1920.

Application filed March 31, 1919. Serial No. 286,227.

To all whom it may concern:

Be it known that I, JULIUS MINTZ, a citizen of the United States of America, residing at New York city, Bronx county, State of New York, have invented certain new and useful Improvements in Check-Perforators, of which the following is a full, clear and exact description.

This invention relates to improvements in perforating devices, but more particularly adapted for check canceling purposes. One of the objects of my invention is to provide a perforating device arranged in the form of a hand-stamp, or in other words, a perforating device arranged to be manipulated in the manner of a hand-stamp. As herein arranged my improved device is arranged to perforate checks (for instance), or to provide means for identification, or for any other purpose. To carry out my improvement, I utilize a plurality of pins or perforating elements and means to automatically select pins to produce perforations in the form of letters (in this instance), although perforations in the form of numerals or other characters could be produced.

I will now describe the device in detail, reference being had to the accompanying drawing, wherein:

30 Figure 1 is an exaggerated fragmentary view of a portion of my improvement;

Fig. 2 is a diagrammatic view of a portion of one of the belts;

Fig. 3 is a similar view illustrating another portion of one of the belts;

Fig. 4 is a side elevation, on a reduced scale of my improvement complete;

Fig. 5 is an end view thereof;

Fig. 6 is a fragmentary plan view, the 40 section being taken on a line 6-6 in Fig. 1; and

Fig. 7 is a similar view, the section being taken on a line 7-7 in Fig. 1, the die-plate and piercing-pins being omitted.

45 My improved perforating device as herein arranged, consists of a frame 8 carrying a plurality of band-members 9, 10, 11 and 12 (see Fig. 5), said belt members passing over a roller 13 at one end of the frame and under a plate 18 at the opposite end of the frame. The belts or bands 9, 10, 11 and 12 may be adjusted or moved for a purpose to be described. Each band-member is provided with patterns in the form of perforations arranged (in this instance) to form letters as indicated in Figs. 2 and 3, the let-

ters, in this instance, being the entire alphabet. Each belt will be provided with perforations arranged to form letters. Fig. 2 illustrates the perforations 14 arranged to 60 form the letter E, and Fig. 3 illustrates said perforations arranged to form the letter I. In this instance each band is provided with twenty six groups of perforations 14, each group being arranged to form some letter 65 of the alphabet. To coöperate with these perforations, I provide a plurality of pins 15 (in this instance twenty-five), grouped as indicated in Figs. 2 and 3, or in other words, arranged in five rows of five pins 70 each. These pins are supported by the frame 8 and are positioned to cause their pointed ends 16 to be located adjacent their coöperating band. Each band 9, 10, 11 and 12 will have a coöperating group of pins 15 75 which will be nested or positioned on the frame 8, between the runs 17 and 18^a of the belts or bands. The pins 15 will be mounted for vertical movement, or movement longitudinally of the frame 8 in one direction by 80 springs 19, and in the opposite direction by a resetting device 20. Adjacent the upper end of the pins, I provide a guide-plate 21, and a guide-plate 22 adjacent the opposite end.

To coöperate with the pins 15 to produce perforations, I provide a die-plate 23 provided with openings 24 to register with the pins 15. The die-plate 23 is yieldably supported by the frame 8, as can be seen in Fig. 90 4, and is provided with arms 25 in the form of yokes to allow sufficient space for the insertion of a check, or other element to be perforated, said check or other element being indicated by the heavy line 26, Figs. 4 and 5. 95 The check, for instance, is placed upon the die-plate 23 under the bands 9, 10, 11 and 12 when it is to be perforated.

The plate 18, which forms the bottom 100 guide for the bands, is provided with openings 27 and is movable transversely of the frame 8. A spring 28 tends to normally maintain the plate 18 in a position as indicated by dotted lines in Fig. 1, or in other words, to the left, maintaining the pins 15 105 and openings 27 in plate 18 out of alignment.

A further feature of the device consists of a locking plate 29 arranged to engage notches 30 or 31 in the pins 15. When the 110 pins are in normal position, or raised, plate 29 will engage notches 30. When the pins

are in lowermost position (see dotted lines Fig. 1), the plate 29 will engage notches 31, said notches being caused to align with said plate 29. In either position the pins will be locked by the plate 29. Both the locking-plate 29 and movable guide-plate 18 may be provided with guide-pins 32 slidably engaging openings in the frame 8.

The restoring or resetting plate 20 is moved longitudinally of the frame 8 in slots 33, one only being shown (Fig. 4), handles 34 being provided to operate the said plate 20.

To operate the device, the bands 9, 10, 11 and 12, or some of them, will be moved to cause any desired letter or character thereon, to assume a position under the plate 18, for instance, letters E, I, A and N. The locking-plate 29 will now be moved toward the right against the tension of its spring 35; this will cause the plate to clear the notches 30 and the springs 19 will force all the pins 15 downwardly against plate 18. The guide-plate 18 will now be forced toward the right against the tension of its spring 28. This movement will cause the openings 27 to align with the pins, and said pins will be forced therethrough by springs 19. Those pins which align with the openings 14 forming the letters (in this instance) in the bands will be forced through said openings and project beyond the bottom surface of the bands. The check or other element to be perforated will now be placed in position as hereinbefore described. After the element to be perforated has been positioned, the frame 8 may be forced down, compressing springs 36 (one only being shown in Fig. 4), thereby forcing the points 37 of the pins 15 through the check and into the alining openings 24 in the die-plate 23. Those pins 15 which have not any alined openings in the bands will rest upon said bands and will not operate to produce perforations. When the pins have been forced down to the utmost the locking-plate 29 will be forced into the notches 31 by spring 35, said plate having been liberated after the pins have been set. The locking-plate 29 locks the pins both when in operative and normal positions. To restore the pins to normal position after the perforating operation has been performed, the plate 20 will be moved up, thereby raising the pins, until plate 29 snaps into the notches 30. The heads 38 of the pins limit their downward movement.

It will be apparent that the character of the perforations is dependent upon what combination of pins is set, said setting being controlled by the perforations in the bands.

Having described my invention, what I claim is:—

1. In a perforating device, an adjustable band having different patterns in the form of openings therethrough arranged to con-

stitute identification symbols, a plurality of piercing-pins adjacent the band, and means to force through the openings in the band forming the desired pattern the pins alining therewith.

2. In a perforating device, an adjustable carrier having different patterns in the form of openings therethrough, a plurality of independently operating piercing pins adjacent the carrier, a locking device to maintain said pins in normal position, and a spring for each pin acting to force its pin through an alining opening of the pattern selected, when said locking device is operated to release the pins.

3. In a perforating device, an adjustable band member, having a plurality of patterns in the form of openings therethrough, a plurality of independently operating piercing pins adjacent the band, a locking device to maintain said pins in normal position, means to force the pins through alining openings of a selected pattern when the locking device is released, and means to restore the pins to normal position.

4. In a perforating device, an adjustable band member, having a plurality of patterns in the form of openings therethrough, a plurality of independently operating piercing pins adjacent the band, a locking device to maintain said pins in normal position, means to force the pins through alining openings of a selected pattern when the locking device is released, means to restore the pins to normal position, and a die-plate having openings alining with the piercing pins.

5. In a perforating device, a die-plate having openings therethrough, a plurality of piercing pins alining therewith, the openings in the die-plate and piercing pins being equal in number, carrier movably mounted and located between the die-plate and pins, said carrier being provided with sets of openings arranged to form different symbols, and means to force those pins which aline with the openings, which constitute a selected symbol, through said openings.

6. In a perforating device, a frame member, a die-plate yieldably secured thereto having openings therethrough, a plurality of piercing pins alining therewith, the openings in the die-plate and piercing pins being equal in number, a carrier movably mounted and located between the die-plate and pins, said carrier being provided with sets of openings arranged to form different symbols, and means to force those pins which aline with the openings, which constitute a selected symbol, through said openings.

7. In a perforating device, a plurality of nested piercing pins, a locking device to maintain the pins in normal position, a carrier having patterns in the form of open-

ings therethrough arranged to be adjusted to cause any of the patterns thereon to register with said nested pins, means to force all of the pins toward the carrier when the locking device is released, said means being arranged to force the pins which align with the openings constituting the pattern through said openings, the remaining pins resting upon the imperforate portion of the carrier.

8. In a perforating device, a plurality of nested piercing pins, a locking device to maintain the pins in normal position, a carrier having patterns in the form of openings therethrough arranged to be adjusted to cause any of the patterns thereon to reg-

ister with said nested pins, means to force all of the pins toward the carrier when the locking device is released, said means being arranged to force the pins which align with the openings constituting the pattern through said openings, the remaining pins resting upon the imperforate portion of the carrier, and means to restore the pins to normal position.

Signed at New York city, N. Y., this 28 day of March, 1919.

JULIUS MINTZ
